WALKING TOY

John W. Ryan, Bel Air, Calif., assignor to Mattel, Inc., a corporation of California
Filed Aug. 4, 1965, Ser. No. 477,146
11 Claims. (Cl. 46—247)

The present application is a continuation-in-part of co-pending application Serial No. 326,544 which is entitled, "Adjustable Walking Toy," and which was filed November 27, 1963, by the applicant herein. In general, the present invention relates to a walking toy. More specifically, the present invention involves a doll adapted to walk independently with natural body and leg motions.

In the past, there have been many attempts to create walking toys, such as walking dolls, to simulate the actual behavior of people or animals. While generally satisfactory, these walking dolls do have certain disadvantages.

One disadvantage resides in the fact that, in power driven toys, the walking action varies in accordance with the amount of power supplied to the toy.

Another disadvantage with certain prior art walking toys resides in the fact that the leg motion is usually a function of the angle between the body unit and the leg unit.

Yet another disadvantage with other prior art walking toys resides in the fact that an unnatural walking action results because there is a fixed orientation of the fore and aft leg motion with a rocking action of the body portion of the toy.

A further disadvantage with some of these prior art walking toys resides in the fact that the toy does not move forward with a constant velocity because of fore and aft inertia loads which make the toy unstable in the forward direction.

A still further disadvantage with prior art walking toys resides in the fact that the entire length of each individual foot of the toy does not contact the floor simultaneously with the result that a heel of the foot usually contacts the floor first giving a point contact which is unstable.

In view of the foregoing factors and conditions characteristic of prior art walking toys, it is the primary object of the present invention to provide a new and useful walking toy not subject to the disadvantages enumerated above and having a body unit, a leg unit and means connecting the body unit and leg unit together for relative rocking action between them.

Another object of the present invention is to provide a new and useful walking toy of the type described having a leg motion which is not a function of the angle between the toy's body unit and its leg unit, but is a function of the rocking angle between the leg unit and the ground.

Yet another object of the present invention is to provide a walking toy of the type described having power means connected to the toy's leg unit and its body unit in such a manner that the toy will move with a uniform velocity regardless of the power supplied to the power unit and the speed thereof.

A further object of the present invention is to provide a walking toy having a cam which is spring loaded against a clutching means in such a manner that, when the cam is employed to drive the fore and aft motion of the toy's legs, leg motion will automatically be oriented to a rocking action between the power unit which carries the cam and the body portion of the toy regardless of the initial position of the legs.

A still further object of the present invention is to provide a new and useful cam for a walking toy which actuates the fore and aft action of the toy's legs in such a

2

manner that the legs are driven back during approximately 80% of the cam rotation and are driven forward during approximately 20% of the cam rotation.

Another object of the present invention is to provide a cam and clutch arrangement for a walking toy which is designed and arranged in such a manner that the legs of the toy can be driven backward but not forward while the weight of the toy is on a particular leg, whereby the cam and clutch arrangement coordinates with a rocking of the leg unit relative to the ground and independent of the rocking of the leg unit relative to the body.

Another object of the present invention is to provide a walking toy of the type described wherein the forward motion of the toy is a substantially constant velocity, thereby avoiding fore and aft inertia loads which tend to make the toy unstable.

Yet another object of the present invention is to provide a new and useful leg and foot arrangement for a walking toy which is so constructed and arranged that the foot will remain parallel to the floor at all times during fore and aft motion of the associated leg, whereby the entire length of the foot contacts the floor uniformly during the ground-contacting portion of each leg stroke.

Another object of the present invention is a walking doll wherein the leg motions are adjustable independently of the body motions.

Still another object of the present invention is a walking toy wherein the body controls the drive means for such toy to synchronize the movement of the body and legs and the drive means.

Still another object of the present invention is a walking doll wherein the body motions include both bending of the torso and twisting of the torso and such bending and twisting motions may be varied independently.

Still another object of the present invention is a walking doll wherein the pivotal attachment between the torso and each of the legs includes a first pivot means for rotating said leg approximately about a side lateral axis of the torso and a second pivot means for rotating said leg approximately about a forward-rear lateral axis of the torso.

Still another object of the present invention is a walking doll which includes control means for each of said legs wherein a first regulator means governs the side angular displacement of the leg and a second regulator means governs the forward-rear angular displacement of the leg.

In general, the present invention involves a toy adapted to walk independently with natural body and leg motions. A first embodiment comprises a body including a torso and legs pivotally attached thereto. The torso has drive means mounted therein for bending the torso and lifting the legs in sequence. Such drive means is controlled by the body to synchronize the movement of the body and the drive means. Also, the drive means is directly connected to the legs to cause the above-described movements of the torso and the legs. The leg motions of the toy may be adjusted independently of the body motions and the toy includes control means for directing the movement of said legs.

According to a second embodiment of the present invention, a new and useful walking toy is provided in the form of a walking doll. The doll includes (1) a body unit comprising a body shell, batteries and miscellaneous switch elements and (2) a leg unit comprising a motor, a motor-gear housing having internal mechanism mounted therein for controlling the operation of the toy and legs which are attached by rigid pivots to the motor-gear housing. An action is provided between the body unit and the leg unit in such a manner that, when the motor is energized, the leg unit will rock, lifting first one foot and then the other off the ground. This is accomplished by

providing a fore and aft pivoting axis between the motor-gear housing and the body shell and by providing a crank. The center line of the crank is placed at a right angle to the pivot axis. This supplies a pure sine wave action to the rocking action between the motor-gear housing and the body shell. The motor is powered by a pair of dry cells which will produce a rocking action of approximately 120 cycles per minute when fully charged and of approximately 80 cycles per minute when under charged. A clutch driven cam is employed to actuate the fore and aft motion of the legs in such a manner that leg motion is automatically oriented to the rocking action between the motor-gear housing and the body shell regardless of the amount of power being supplied to the motor. Each leg is connected to an actuator which is driven by the cam. The actuator is connected to its associated leg through a system of spring washers and detent means which are locked in position during the walking action, but which may be overcome to facilitate placing the doll in a sitting position. Each foot of the doll is connected to its associated leg and to the actuator assembly in such a manner that each foot is kept parallel with the ground during fore and aft motion of its associated leg, whereby each foot will contact the floor uniformly throughout the length of each step.

The cam includes a slot which has two slopes arranged to drive the leg actuators in such a manner that the legs will be driven backward during 30% of the cam rotation and driven forward during 20% of the cam rotation. The slope of the section of the cam which drives the legs forward is four times as great as the slope of the section of the cam which drives the legs backward. When a leg is on the ground, the clutching action of the cam is great enough to overcome the small slope of the section of the cam that drives the leg back. Therefore, a particular leg will be driven back until the actuator reaches the top end of this section of the cam. At this point, the steepness of the slope of the cam that drives the leg forward is sufficient to slip the clutch. This holds the cam stationary until the weight of the doll is shifted to the other foot. At this point, the actuator of the opposite leg will be at a point on the cam where it will, in turn, drive the leg back. Thus, the difference in slope of the fore and aft sections of the cam in conjunction with the clutching torque will allow a foot to be driven back, but not forward, while the weight of the doll is on that particular foot. In this way, the cam will be slipped rotatably until it coordinates with the rock of the leg unit relative to the ground and independent of the rocking of the leg unit relative to the body unit.

The cam is designed in such a manner that a particular foot starts its backward motion before it contacts the floor. The cam is also designed to give a constant velocity stroke to the leg action. Thus, the doll has a forward motion of a more or less constant velocity avoiding fore and aft inertia loads that tend to make the doll unstable.

The features of the present invention which are believed to be novel are set forth with particularity in the appended claims. The present invention, both as to its organization and manner of operation, together with further objects and advantages thereof may best be understood by reference to the following description, taken in connection with the accompanying drawings in which like reference characters refer to like elements in the several views.

In the drawings:

FIG. 1 is a side cross-sectional view of a first specific embodiment of the walking doll of the present invention.

FIG. 2 is a cross-sectional view of FIG. 1 taken along the lines 2-2 of FIG. 1.

FIG. 3 is a perspective view of a portion of FIG. 2 showing the means pivotally attaching each leg to the torso.

FIGS. 4-6 are schematic views shown a portion of the operation of the doll wherein FIG. 4 shows the position

of the shaft portion of the crank means, FIG. 5 shows the corresponding front view of the doll, and FIG. 6 shows the corresponding side view of the doll at the height of a step.

FIGS. 7-9 are similar to FIGS. 4-6, except that the corresponding positions are shown at the end of a step forward by the left doll foot.

FIGS. 10-12 are similar to FIGS. 4-6, except that the positions are shown for the height of a step for the right foot.

FIGS. 13-15 are similar to FIGS. 4-6, except that the corresponding positions are shown at the end of a step forward by the right foot.

FIG. 16 is a partial, side-elevational view of a walking toy constituting a second embodiment of the present invention.

FIG. 17 is a vertical cross-sectional view of the walking toy of FIG. 16.

FIG. 18 is a cross-sectional view similar to FIG. 17 taken at right angles thereto.

FIG. 19 is an enlarged cross-sectional view taken along lines 19-19 of FIG. 18.

FIG. 20 is a graphical representation of a cam employed in the walking toy of FIG. 17.

FIG. 21 is a diagrammatic side view of the walking toy of FIG. 17 showing the relationship of relative positions of its legs with respect to the cam of FIG. 20 during a walking operation.

FIG. 22 is a diagrammatic front view of the toy of FIG. 17 showing the position of its leg in relationship to the cam of FIG. 20 during a walking operation.

FIG. 23 is an elevational view of one of the legs of the toy of FIG. 17 showing, in broken lines, the relationship of the foot of the toy with respect to the leg during a walking operation.

FIG. 24 is a diagrammatic view illustrating the rocking mode of the toy of FIG. 17 at approximately 30 r.p.m.

FIG. 25 is a diagrammatic view similar to FIG. 24 showing the rocking mode at approximately 120 r.p.m.

FIG. 26 is an exploded, perspective view showing a modified form for the toy of FIG. 17.

FIG. 27 is an enlarged, exploded, perspective view of the leg structure and actuator of the toy of FIG. 26.

FIG. 28 is an enlarged elevational view, with parts shown in cross-section, of the toy of FIG. 26.

FIG. 29 is an enlarged, partial cross-sectional view taken along line 29-29 of FIG. 28.

FIG. 30 is an enlarged bottom view of one foot portion of the toy of FIG. 26.

FIG. 31 is an enlarged, exploded perspective view of portions of one leg and foot assembly for the toy of FIG. 26.

FIG. 32 is an exploded perspective view of the motor-gear assembly which is shown in FIG. 26 and which may be used in the toy of FIG. 17.

FIG. 33 is a cross-sectional view of the motor-gear assembly of FIG. 17.

In general, as illustrated in FIGS. 1-3, the first embodiment of the present invention involves a bilaterally symmetrical doll 20 which is adapted to walk independently with natural body and leg motions and to have the leg motions adjustable independently of the body motions and the body motions adjustable independently of each other. The doll 20 comprises a body 21, including a torso 22 with legs 80 attached thereto by a pivotal attachment 60. The torso 22 has drive means 40 mounted therein for sideways bending and twisting of the torso and lifting the legs 80 in sequence. The drive means 40 is controlled by the body 21 to synchronize the movement of the body 21 and the drive means 40. Also, the drive means 40 is directly connected to the legs 80 to cause said movements of the torso 22 and the legs 80. In addition, the doll 20 includes control means 81 for directing the movement of the legs 80.

The torso 22 comprises a front wall 23 and a rear wall 24 which are oriented substantially perpendicular to a forward-rear lateral axis 25 of the torso 22. Similarly, the torso 22 has side walls 26 and 27 which are oriented substantially perpendicular to a side lateral axis 28 of the torso 22. The torso 22 has holes 29 in its lower portion through which the drive means may be directly connected to the legs 80 and preferably holes 30 for connecting arms 31 and a hole 32 for connecting a head 33 to the torso 22. The arms 31 and the head 33 may be connected to the torso 22 by any conventional means.

The drive means 40 for the doll body 21 comprises a rotatable crank means 41 connecting the torso 22 to the legs 80 and adapted to periodically bend the torso 22 and the legs 80 towards each other, twist the torso 22 with respect to the legs 80 and lift the legs 80 with respect to each other alternately to each side. The crank means 41 are rotated by a gear means 50 and the gear means 50 in turn are driven by a motor means 55. The crank means 41 comprises a substantially offset shaft 42 having a central body 43 with angle arms 44 at each end extending in substantially opposite directions from the axis of the central body 43. Preferably, the angle arms 44 have an angle of 180° therebetween so that the movement of each leg 80 is 180° from the other leg 80, i.e., the leg movements are equally spaced. Also, preferably, the angle arms 44 extend at substantially right angles to the central body 43. However, other angles may be utilized, as discussed below in connection with the description of the operation of the present invention. Extending outwardly at the outer end of each angle arm 44 is a finger 45 at an acute angle to the axis 43' of the central body 43 of the shaft 42. The axes 45' of the fingers 45 are displaced from each other. The shaft 42 is mounted on the bottom wall 34 of the torso 22 by means of a pair of posts 46 having coaxially aligned holes 47. Seated in the holes 47 of the posts 46 are bearings 48 through which the central body 43 of the shaft 42 extends.

The gear means 50 of the drive means 40 includes a first gear 51 fixedly mounted on the central body 43 of the shaft 42 and a second gear 52 engaged with the first gear 51. The second gear 52 is in turn operatively connected to a gear box 53 by means of a shaft 54 on which it is fixedly mounted. The gear box 53 is in turn connected to a motor means 55 which is adapted to drive the gear means 50. The gear box 53 contains a conventional gearing arrangement for suitably adjusting the speed of the motor means to the desired rate of rotation of the crank means 40. Both the gear box 53 and the motor means 55 are mounted on a stand 56 which is in turn connected to the rear wall 24 of the torso 22.

The pivotal attachment 60 between the torso 22 and each of the legs 80 comprises a first pivot means 61 for rotating the leg 80 approximately about a side lateral axis of the torso, i.e., an axis parallel to the side lateral axis 28. The first pivot means 61 comprises a block 62 joined to the leg 80 having a bore 63 extending approximately parallel to a side lateral axis of the torso. The finger 45 of the drive means 40 is rotatably received in the bore 63 of the block 62. The pivotal attachment 60 also includes a second pivot means 70 for rotating the leg 80 approximately about a forward and rear lateral axis of the torso 22, i.e. an axis parallel to the forward-rear axis 25. The second pivot means 70 comprises a yoke 71 which is joined to the leg 80 by mounting the yoke 71 on a plate 75 embedded in leg 80. The yoke 71 has a rod 72 extending between its ears 73 which extends approximately parallel to the forward-rear lateral axis of the torso 22. The second pivot means 70 also includes a second bore 74 in the block 62 of the first pivot means 61 in which the rod 72 of the yoke 71 is rotatably mounted.

The movement of the legs 80 is directed by the control means 81. The control means 81 comprises for each of the legs 80 a first regulator means 82 for governing the side angular displacement of the legs 80 and a second 75

regulator means 90 for governing the forward-rear angular displacement of the leg 80. The first regulator means 82 comprises a hanger 83 mounted within the torso 22 having a folding means in the form of an aperture 84 therethrough. The first regulator means 82 also includes a strut 85 with its first end 86 fixed to the yoke 71 which is in turn joined to the leg 80 and its second end 87 slidably received in the aperture 84 of the hanger 83. The holding means is adapted to restrain the side angular displacement of the second end 87 of the strut 85.

The second regulator means 90, similar to the first regulator means 82, comprises the hanger 83 having a holding means in the form of an aperture 84 therethrough and the strut 85 with its first end 86 fixed to the yoke 71 and its second end 87 slidably received in the aperture 84 of the hanger 83. However, in the case of the second regulator means 90, the holding means is adapted to restrain the forward-rear angular displacement of the second end 87 of the strut 85. In addition, the second regulator means 90 includes a bracket 91 rotatably mounted at its first end 92 about a side lateral axis in the upper portion of the torso 22. More specifically, the first end 92 of the bracket 91 is rotatably mounted on a rod 93 and separated therefrom by bearings 94. The rod 93 extends parallel to a side lateral axis of the doll torso 22 and is mounted on the ribs 95 extending between and attached to the front wall 23 and rear wall 24 of the torso 22. The second end 96 of the bracket 91 is operatively connected to the drive means 40 to follow the forward-rear movement of the drive means 40. More specifically, the second end 96 of the bracket 91 has a slot 97 therein in which is slidably received the finger 45 of the drive means 40. The configuration of the slot 97 is such that the up-and-down movement of the finger 45 caused by the rotation of the crank means 41 does not move the bracket 91 while the forward-rear movement of the finger 45 is directly translated to the bracket 91. The hanger 83 is mounted on the bracket 91 adjacent to the leg 80 and preferably, as shown, the hanger 83 is simply punched out of the bracket 91. Also, preferably, the forward-rear movement of the bracket 91 is insured by a pair of spaced parallel guide bars 98 which extend between and are attached to the front wall 23 and rear wall 24 of the torso 22. The bracket 91 is slidably received between the guide bars 98 whereby they form a track upon which the bracket 91 travels.

When the doll 20 is actuated to start walking, the motor means 55 rotates the crank means 41 of the drive means 40 which causes the offset shaft 42 to rotate. The effect of the rotation of the shaft 42 is relatively complex with respect to the torso 22 and the legs 80 and may best be explained by discussion each portion of the configuration of the shaft 42 with respect to the relative movement which such configuration causes between the legs and the torso.

If the shaft 42 were formed as illustrated in Sketch A below, the rotation of the shaft would merely lift one leg with respect to the other leg without causing any bending or twisting of the torso with respect to the legs. Of course, there would be some bending of the body with respect to the surface upon which the doll is walking. However, such bending would be similar to the mechanical type of motion associated with prior art walking dolls.

Sketch A

On the other hand, if the shaft 42 were shaped as illustrated in Sketch B below, wherein the fingers of the shaft are coaxially aligned, the resulting motion would involve merely the bending and twisting of the torso with respect to the legs without any lifting of the legs with respect to each other.

Sketch B

However, as set forth above, the configuration of the shaft is as illustrated in Sketch C below, wherein the fingers are at an acute angle to the central body of the shaft but are axially displaced from each other. With such configuration, the rotation of the shaft causes not only the legs to lift with respect to each other, but also the torso to bend and twist with respect to the legs. Thus, the center or rotation of the shaft is displaced from the axis 43' of the central body 43 of the shaft and from the axes 45' of the fingers 45, as illustrated in FIGS. 4, 7, 10 and 13.

Sketch C

It should be noted at this point that a possible alternate embodiment of the shaft may have the configuration as illustrated in Sketch D below, wherein the fingers are set at an acute angle to the axis of the central body of the shaft and are displaced with respect to each other, but are joined directly to the shaft.

Sketch D

However, it is preferred to utilize angle arms 44 as set forth above in Sketch C and in the drawings (FIG. 2, for example), since they produce a substantial lifting motion between the legs while requiring only relatively short fingers, i.e., a greater displacement between the fingers can be achieved thereby. More important, the angle arms 44 facilitate independent adjustment of the lifting motion as compared to the bending and twisting motion between the torso and the legs.

It should be noted at this point that the foregoing analysis of the effect of the rotation of the shaft on the torso and legs has ignored any possible rotation of the leg with respect to the shaft for purposes of simplicity. However, in order to understand the actual walking motion of the doll of the present invention, it is necessary that any rotation of the legs with respect to the shaft be included in the total analysis of the operation. Consequently, the rotation of the leg with respect to the shaft will be discussed at this point before the over-all operation of the doll is discussed. As set forth above, the doll 20 includes a second pivot means 70 for rotating the leg 80 approximately about a forward-rear lateral axis of the torso 22. Thus, when considering the second pivot means 70 alone, the leg 80 is capable of a side angular displacement either to or from the body until the adjoining portion of the leg actually strikes the torso. For this reason, contrary to the foregoing analysis involving solely the effect of the rotation of the shaft on the torso and legs, the side angular displacement of the leg is completely independent of the rotation of the shaft and of the torso. In other words, when the second pivot means 70 is considered alone, the bending motion and twisting motion of the torso are rendered independently of each other, since the twisting movement continues to be regulated by the rotation of the shaft, while the bending movement is completely independent of the movement of the shaft. However, as set forth above, the doll 20 also includes a first regulator means 82 for governing the side angular displacement of the leg. The operation of the first regulator means 82 involves the tilting outward of the leg 80 as the finger 45 of the shaft 42 moves upwardly, since the strut 85 is caused to rotate towards a

horizontal position as the rod 72 approaches the aperture 84 and the converse movement takes place during the downward movement of the finger 45 during the rotation of the shaft 42. Thus, the first regulator means 82 does govern the side angular displacement of the leg 80 in coordination with the rotation of the shaft 42 and causes the leg 80 to have a side angular displacement during the rotation of the shaft 42. In short, the second pivot means 70 makes only the bending of the body independent of the movement of the leg 80 without affecting the relationship of the twisting of the body and the leg and also makes the side angular displacement of the leg independent of the rotation of the shaft, but the first regulator means 82 forms a new relationship between the rotation of the shaft and the side angular displacement of the leg and makes such relationship adjustable, depending on the position of the first regulator means 82.

As set forth above, the first pivot means 61 permits the rotation of the leg approximately about the side lateral axis of the torso, i.e., about the shaft 42 or, more particularly, the finger 45. Thus, when considering the operation solely of the first pivot means 61, when the shaft 42 is rotated the leg 80 simply rotates a corresponding amount relative to the shaft 42 and no forward nor rear angular displacement of the leg 80 takes place. However, the doll 20 also includes a second regulator means 90 for governing the forward angular displacement of the leg 80. In operation, the second regulator means 90 includes the hanger 83 with an aperture 84 in which the second end 87 of the strut 85 is slidably received. Since the first end 86 of the strut 85 is fixed to the leg 80, the rotation of the shaft 42 and consequent forward-rear movement of the finger 45 causes an angular displacement of the leg 80 about the finger 45 due to the rotational force exerted thereon by the strut 85. In addition to the foregoing movement, the operation of the second regulator means 90 involves the forward angular displacement of the bracket 91 by the forward movement of the finger 45 during the rotation of the shaft 42. Such forward movement of the bracket 91 causes a corresponding forward movement of the aperture 84 in the bracket 83. Consequently, the resulting forward angular displacement of the leg 80 is restricted. Also, the side angular displacement of the leg is rendered independent of the forward-rear angular displacement of the leg, since the forward-rear displacement can be regulated by the bracket 91 independent of the holding means or aperture 84.

When the aforescribed separate operation of the various parts of the doll are brought together, as they are in the doll 20, the over-all walking motion of the doll 20 may be explained. As partially illustrated in FIGS. 4-6, the initial movement of the body involves substantially side-to-side bending and twisting of the torso 22 with respect to the legs 80 and forward-and-side angular displacement of the legs 80 without substantial lifting of the legs 80 during such movement. Such initial movement may be explained by the following theory of the operation of the invention. However, this theory should be regarded as merely a probable explanation for the unusual and unexpected results achieved by the present invention and not as a limitation upon the invention. The initial movement apparently involves the interaction between the natural period of oscillation or rocking of the doll body 21 and the movement of the drive means 40. Because of the relatively large mass involved in the torso 22 and the small power output of the motor means 55, the initial movement imparted to the body 21 by the motor means 55 is not sufficient to raise the legs 80. However, once an oscillatory or rocking motion has been imparted to the doll body 21, the additional impulses imparted by the successive rotations of the drive means 40 reinforce the oscillatory movement of the doll body 21 so that the lifting of the legs is commenced.

After the initial period of movement without substantial lifting of the legs 80, the doll, when moving its body

21 to the left, for example, will simultaneously bend the left shoulder to the side and twist it forward and raise the leg 80 with both a side angular displacement and a forward angular displacement. Such movement represents a realistic reproduction of the natural body motions during walking. When the drive means 40 initiates the bending and twisting of the doll body 22, the angle between the fingers 45 and the central body 43 of the shaft 42, coupled with the angle arms 44, are adapted to both twist and bend the torso 22 with respect to the legs 80 and to lift the legs 80 with respect to each other. However, as set forth above, the first pivot means 61 eliminates any direct mechanical connection between the bending of the torso 22 and the legs 80, although such connection is retained between the twisting of the torso 22 with respect to the legs 80. In addition, the first regulator means 32, when coupled with the second pivot means 70, may be adapted, for example, to generate an angle of 165° between the torso 22 and the leg 80 by the side angular displacement of the leg 80. Since the torso 22 is relatively heavier than the leg 80, i.e., the torso 22 has a greater moment of inertia than the leg 80, the movement of the drive means 40, rather than the direct mechanical connection thereof between the torso and the leg, achieves the predominant result of bending the leg 80 upward, rather than bending the torso 22 downward, bringing these two doll parts together. Counterbalancing such effect is the force of gravity on the torso 22 and leg 80 which, absent the other forces involved, tends to cause the torso 22 to move downward while the leg 80 remains stationary. The resultant effect of the mechanical action between the leg and the torso and drive means, as well as the remainder of the forces created by the doll movement, is designed to bend the torso 22 through an angle of about 7-8°, while the leg 80 raises to a height of about 0.1 to 0.2 inch. Of course, by suitably varying the design of the doll, e.g., varying the weight or configuration of the torso or legs, the legs may move through a greater or lesser angle than the torso. Even more important, merely by varying the speed of the drive means control of the relative movement between the legs and torso may be achieved. Thus, at very high speeds, the torso may not substantially bend at all. However, it has been found that for a total angle of bend of about 7-8°, a speed which produces an angle of about 3° for the torso and about 4-5° for the legs with respect to the surface on which the doll is standing is preferable. It would appear that the direct mechanical connection of the leg to the drive means and body, coupled with the greater moment of inertia of the torso 22, has a greater effect on the resulting bending of the leg 80 than the force of gravity on the torso 22 because the doll is displaced to a relatively small angle from a vertical position. In other words, the effect of the force of gravity is substantially nullified, since it is exerting only a relatively small bending moment.

An alternate and more concise way of describing the resultant movement of the torso with respect to the legs involves considering the relative accelerations. When the angle is formed between the torso and legs alternately to each side, both the torso and the legs are moved from a position at rest so that they are both accelerated. Since the legs are accelerated faster than the torso, they move up relative to the torso. More specifically, although the acceleration due to gravity aids the torso and hinders the legs, the acceleration due to the drive means is much greater on the legs than on the torso. Consequently, the resultant relative acceleration moves the legs upward with respect to the torso.

Another factor which must be considered is the effect of the moving part of the body on the relatively stationary part, e.g., the effect of the moving foot on the foot remaining on the floor. For example, when the left foot takes a step (FIGS. 4-9), if we assume there is no body twist and the right foot is securely fastened to the floor, then the resulting body movement would be as illustrated

in FIGS. 4-9. However, if the right foot is free to move as it actually is and there is no body twist, then when the left foot and the body move forward, they exert a turning force on the right foot. Thus, when viewed from above, the body would rotate in a counterclockwise direction during a step by the left foot and in a clockwise direction during a step by the right foot. Such result is prevented by twisting the body a sufficient amount in the opposite direction so that the two movements are effectively cancelled and the body remains facing forwardly during each step. Experimentally, for the dolls tested to date, about a 5° body twist is sufficient.

From the foregoing theories, the initial lifting of the leg can be understood. Thus, as illustrated in FIGS. 10-15, after the completion of one step the identical sequence takes place with respect to the other end as the doll then bends to the right. The result is that the doll moves one foot in front of the other in sequence, utilizing both a side and a forward angular displacement and, in addition, has a corresponding bending and twisting of the body. Thus, the doll walks in a natural fashion, bending not only to the side, but also twisting the body to correspond to the movement of the particular leg.

However, although the foregoing explanations or theories are sufficient to explain the walking motion of the doll of the present invention, they do not take into account the problems encountered in actual practice. As noted above, the doll body has a natural period of oscillation which is dependent upon its particular construction, e.g., the particular size, weight and placement of the various doll parts, but is independent of the particular drive means utilized. Therefore, it is possible, without controlling the drive means by the body as in the present invention, for the drive means to oppose the natural oscillation of the doll body. For example, if the movement of the doll body is not synchronized with the drive means, the doll body movement may be trying to lift one leg, while the drive means may be trying to lower the same leg so that the doll may merely stand on one leg while waving the other leg or tip over. In the present invention, such problem is solved by having the body control the drive means so that the movement is synchronized, i.e., the body achieves a governor action with respect to the drive means.

Such governor action or synchronization occurs in the present invention since, when the doll 20 reaches a maximum height of a step, the motor means 55 of the drive means 40 slows down so that the drive means maintains the synchronization between the natural oscillation of the doll body and the movement of the drive means. For example, when the motor is heated the doll takes correspondingly short, quick steps with relatively a smaller amount of lifting of the leg from the surface upon which the doll is walking. On the other hand, when the motor is slowed down, the doll takes slow, large steps with a relatively high raising of the leg during each step. In any case, the motor means 55 of the drive means 40 slows down during the step so that the drive means movement is maintained in synchronization with the natural oscillation of the doll body. Such operation may be explained by the following theory or explanation. However, such theory should be regarded as merely a probable explanation for the unusual and unexpected results achieved by the present invention and not as a limitation of the invention.

As the doll body 20 approaches the height of a step, the drive means 40 reverses its motion so as to start the body bending and twisting, as well as the leg lifting in the opposite direction. However, the momentum of the doll body tends to continue to move the leg upward and to bend and twist the body in the initial direction. In addition, in moving the body when it is bent to one side to a bent position on the other side, the center of gravity of the body must be lifted while the body is moving toward a vertical position. Consequently, although the

drive means attempts to start bending and twisting the body in the opposite direction, as well as lifting the legs in the opposite direction, the movement and position of the doll body, at least initially, results in a resultant force which is more powerful than the force exerted by the motor on the drive means so that the drive means is slowed down by the doll body. Once the doll body movement has been overcome and the position has been brought to an upright position, the restraining force of the body on the drive means is released so that the natural step movement described above can take place.

Another factor which must be considered in connection with the above discussed body motions is the orientation of the body at the change-over point. The changeover point is considered the point during the rocking motion of the doll when both feet are on the floor and the weight of the doll body is substantially equally supported by each leg. It has been found that for proper rocking, the center line of the body should be substantially vertical at the changeover, otherwise an unstable condition is promoted during oscillation. Also, although rocking can be obtained by moving a large body mass through a small displacement, it has been found preferable to utilize a small body mass moving through a relatively large displacement. Such arrangement simplifies rocking, since the doll becomes self-starting, i.e., the doll will begin rocking from an at-rest position when power is applied.

An alternate way of describing the synchronization of the doll body and drive means involves considering the acceleration and deceleration of the doll body. Assuming the center line of the body is substantially vertical at the changeover point, the body displacement will be at a maximum angular velocity and zero acceleration at the changeover point. On the other hand, as the body displacement increases, it is decelerated until at maximum displacement the velocity is zero and the deceleration is at a maximum. When the resulting forces are transferred to the drive means, it is slowed down.

From the foregoing explanation it can be seen that the body does, indeed, control the drive means to synchronize the movement of the body and the drive means. Also, it should be noted that the foregoing relationship permits a relatively small motor to be utilized in the drive means; since the synchronization of the body and the drive means makes use of both the natural oscillation of the body and the power output of the motor. Consequently, only a small energy input is required for each step to maintain the walking motion and only a very small motor need be utilized in the doll body.

Referring again to the drawings and particularly to FIGS. 16-25 and 33, a bilaterally-symmetrical walking toy constituting a second embodiment of the present invention, generally designated 110, includes a head 111, a body unit 112 having a torso or body shell 114 and a pair of batteries 116 and a pair of arms, such as the one shown at 117. The toy 110 also includes a leg unit 118 having an electric motor 120, a motor-gear housing 122 and a pair of legs 124.

The body shell 114 includes a front wall 126, a rear wall 128, a pair of spaced sidewalls 130 and a bottom wall 132. The body shell 114 may be manufactured from any suitable material employing any suitable manufacturing technique such, for example, as by injection molding a suitable plastic in two operations. In a first molding operation, a front body half 134 (FIG. 26) is formed including the front wall 126 and one-half of each side wall 130 as an integral unit. In a second molding operation, a rear body half 136 is formed including the rear wall 128 and one half of each side wall 130 as an integral unit. The front body half 134 and the rear body half 136 may be joined together by engaging hollow, cylindrical bosses 137 provided on the rear body half 136 with pins 138 carried by the front body half 134. An adhesive weldment 139 may be used, if desired, to seal the body halves together. During the molding opera-

tion, the rear body half 136 is provided with (1) a pair of battery chambers 140 for housing the batteries 116, (2) a bracket 142 for supporting a crank slot 144 and (3) a cylindrical boss 146 for swingably mounting the rear portion 147 of the motor-gear housing 122. Also, during the molding operation, the front body half 134 is provided with a cylindrical boss 148 for swingably supporting the front portion 149 of housing 122 and each side wall 130 is provided with an upper arm-receiving aperture-half 150 and a lower, leg-receiving aperture-half 152.

The motor-gear housing assembly 22 shown in FIGS. 17-19 and 33 and a modified housing 122a shown in FIGS. 26 and 32 are also preferably molded in two pieces by injection molding techniques employing a high impact polystyrene plastic. The housing 122 differs from the housing 122a essentially only in that the housing 122 has a rectangular upper portion while the upper portion of housing 122a is cylindrical. The housing 122 includes a front wall 154, a top wall 156, a rear wall 158, side walls 160 and a bottom wall 162. The housing 122a includes an encompassing side wall 160a, a front wall 154, a top wall 156, a rear wall 158 and a bottom wall 162. An electric motor chamber 164 and a gear chamber 165 are formed in the housing assemblies 122 and 122a by providing them with a partition 166 intermediate their respective top walls 156 and the bottom walls 162. The electric motor 120 may be resiliently mounted in either chamber 164 on rubber grommets 168 which are carried by the motor 120 and which are disposed within suitable apertures 170 and 172 provided in the top wall 156 and the partition 166, respectively. The electric motor 120 includes a first end plate 174 which carries one grommet 168 and a second end plate 176 which carries the other grommet 168. The motor 120 also includes an armature shaft 178 having a first end 180 extending through the end plate 174 and a second end 182 extending through the end plate 176. The end 180 carries a fly wheel 184 and the end 182 carries a driving gear 186. The driving gear 186 drives a gear reduction system which is indicated generally at 188 (FIGS. 17, 32 and 33) and which includes first, second and third gears 190, 192 and 194, respectively, adapted to obtain an output-shaft rate in the range of 120 to 80 r.p.m. depending upon the strength of batteries 116. The gear 190 is preferably manufactured from a rubber-like material, such as a rubber-like plastic, to minimize noise in the toy 110. The gear 190 is rotatably mounted on a crank shaft 196 and includes a large-diameter portion 202 on the gear 192. The gear 192 includes a shaft 203 which is rotatably mounted in a pair of brackets 204 carried by the front wall 154 of the housing assemblies 122 and 122a. The gear 192 also includes a small-diameter portion 208 meshing with a set of teeth 210 provided on the gear 194. The gear 194 is keyed to the crank shaft 196 by a key 212 for imparting rotation thereto. The shaft 196 is preferably made of steel and includes a first end 214 which is rotatably mounted in an aperture 216 provided in the partition 166 and a second end 218 which is provided with an enlarged head portion 220. A steel ball 222 is affixed to the head 220 near one edge thereof giving a crank effect.

Either housing assembly 122 or housing assembly 122a may be swingably mounted in, or centrally disposed in the plane of symmetry of, the body shell 114 by engaging the front boss 148 and the rear boss 146 by counter bores 224 and 226, respectively, which are provided on the portions 149 and 147 of housing assemblies 122 and 122a, respectively. The ball 222 works in the slot 144 in such a manner that rotation of the crank shaft 196 produces a relative rocking action between the housing assemblies 122 and 122a and the body shell 114 forcing a sine wave form. This is accomplished by placing the center line of action of the crank 196 at a right angle to the pivot axis formed by the bosses 148 and 146 and their associated counter bores 224 and 226, respectively.

The legs 124 (FIGS. 17, 18 and 23) are connected to the housing assembly 112 by rigid pivots, indicated generally at 228, so that the complete leg unit 118 will rock with respect to the body unit 112 lifting first one foot 230 and then the other foot 232 off the ground. This is accomplished by the pivotal mounting of the housing assembly 122 coupled with the action of the crank 196. The type of rocking action obtained by this forced rocking between the leg unit 118 (housing assembly 122 and legs 124) and the body unit 112 will be readily understood by referring to FIGS. 24 and 25. The action shown in FIG. 25 is one normally encountered at high rocking speeds of approximately 120 cycles per minute. The rocking action shown in FIG. 24 is one that is normally encountered at lower speeds of approximately 80 cycles per minute. Assuming that FIGS. 24 and 25 are drawn from the back of the walking toy, it will be noted that in FIG. 25 the left foot 230 is on the ground 234 when the body unit 112 is rocking to the right and the right foot 232 is on the ground 234 when the body unit 112 is rocking to the left. In a rocking situation of this type, the right leg 124 must move forward when the body unit 112 is rocking to the right, relative to the leg unit 118. Contrary to this in the rocking system shown in FIG. 24, the right foot is on the ground 234 when the body unit 112 is rocking to the right and the left foot 230 is on the ground 234 when the body unit 112 is rocking to the left. In this situation, the right foot 232 must move forward when the body unit 112 is rocking to the left, as viewed in FIG. 24. Since the walking toy will move in both the 30 r.p.m. rocking mode and the 120 r.p.m. rocking mode, it can be seen that the motion of legs 124 cannot be a function of the rocking angle between the legs 124 and the ground 234, or other surface, upon which the walking toy 110 travels. This situation is further complicated by the fact that there is no definite transition point between the two rocking modes, but rather a smooth change as the walking speed increases.

A series of experiments were undertaken to study the modes of rocking motion and power consumption of the walking toy 110 for the purpose of optimizing its operating parameters. The objective was to define a region of operating range for the toy for minimum power requirement and maximum rocking stability. A region of stable rocking motion was found. A pertinent physical parameter is the product of the body unit moment of inertia times the maximum driving amplitude angle times the cosine of the tilt angle. The experiments indicated that the power required is almost proportional to frequency and is only slightly dependent on the product of the body unit moment of inertia times the maximum driving amplitude angle times the cosine of the tilt angle. This indicates that the toy 110 is a constant torque device and that the power requirement will decrease with the lower frequency. With a gear ratio of 32:1, the no-load gear train torque loss is about 3.5 gr./cm. at the motor input shaft. The average torque for normal operation ranged from 5 to 12 gr./cm., although the instantaneous torque was sometimes as high as 25 gr./cm. For a given configuration, generally, at high driving frequency the body unit 112 leads the leg unit 118 by 160 degrees in phase, i.e., they are rotating in opposite directions. As the driving frequency decreases, the phase shift becomes less and less. It was observed that the toy 110 cannot be made to operate when the phase lead becomes less than 90 degrees. It was also observed that the foot lift increases with the decreased rocking frequency. This is expected because of the non-linear nature of the system. The center of gravity of the body unit 112 is approximately at the location of the batteries 116 and the center of gravity of the leg unit 118 lies on the pivot axis thereof. The leg unit 118 has less mass than the body unit 112. The relationship between these masses, the centers of gravity of the two units, the rocking frequency and the amount of rocking motion between the two units governs the type of

walking action produced. It has been found that an angle of 30 degrees between the body unit and the leg unit produces a satisfactory amount of rocking motion.

Although various methods can be employed to coordinate the action of the legs 124 with the rocking of the leg unit 118 relative to the ground 234, the method shown and described herein for purposes of illustration, but not of limitation, may employ a clutch driven cam assembly 236 (FIGS. 17, 19 and 33) to actuate fore and aft motion of the legs 124. The clutch driven cam assembly 236 includes a plastic bearing 238 having a hub portion 240 which is journaled in an aperture 242 provided in the bottom wall 162 and an enlarged annular portion 244 having an upper face 246 providing a clutch surface. The bearing 238 is keyed to the shaft 196 by a key 248 for rotation thereby.

The clutch driven cam assembly 136 also includes a cam 249 having an upper cam half 250 and a lower cam half 252 which are rotatably mounted on the shaft 196 in telescopic relation in such a manner that they form a cam slot 254. The upper half 250 includes a clutch face 256 which is biased into engagement with a like clutch face 258 provided on the gear 194 by a compression spring 260 which encompasses the shaft 196 and which engages the cam halves 252 and 254 in such a manner that it tends to spread them apart. The cam half 252 is also provided with a clutching surface 262 which engages the clutch face 246 provided on the bearing 238. The spring 260 is loaded against the cam halves 250 and 252 with a spring load sufficiently light to allow the shaft 196 to continue rotation when the cam halves 250 and 252 remain stationary. In this way, the cam driven clutch assembly 236 can be oriented to the shaft 196 in any position. Since the cam assembly 236 is used to drive the fore and aft motion of the legs 124, this motion can, therefore, be oriented to the rocking action between the leg unit 118 and the body unit 112 at any position.

As best shown in FIG. 19 each leg 124 is rigidly connected to the housing 122 by a leg actuating assembly 228 which includes an axle 270 having an internally threaded end 272 and an end 274 near which a flanged arm 276 is provided. The end 274 may be inserted through an aperture 278 provided in the side walls 160 of the housing 122 after which a washer 280 may be placed over the end 274 which is peened over against the washer 280 as indicated at 282. Each flanged arm 276 carries a pin 284 which engages an aperture 286 provided in the housing 122 to prevent the axle 270 from rotating. Each flanged arm 276 is provided with suitable detents, such as the one shown at 288, which are positioned adjacent a hub 290 provided on the axle 270. An actuator link 292 having an arm 294 which carries a pin 296 and an apertured flange 298 may be installed on the hub 290 in such a manner that a slot 300 provided on the flange 298 engages an associated detent 288 provided on the axle 270.

The mechanism 228 also includes a detent ring 302 which is provided with an annular flange 304 intermediate its ends 306 and 308. The flange 304 is provided with a plurality of detents, such as the one shown at 310, which are engageable with suitable slots, such as the one shown at 312, provided on an actuator assembly 314 when it is in position on the end 306 of the detent ring 302. The detents 288 are caused to engage their associated slots 300 and the detents 310 are caused to engage their associated slots 312 by a pair of spring washers 316 each of which has suitable resilient fingers, such as the one shown at 318 for each washer 316, adapted to force the actuators 314 and the actuator links 292 into engagement with their associated detent means. The spring washers 316 exert a sufficient force so that the actuator links 292 and the actuators 314 will move the legs 124 in a manner to be hereinafter described, but are sufficiently light so that the legs 124 may be swung by hand to overcome the spring tension so that the toy 110 may be placed in a seated position wherein the legs 124 are at right angles to the body unit 112.

The legs 124 are connected to the mechanism 228 by a log cap 320 having a hub portion 322 which is mounted on the end 308 of the detent ring 302 and which is prevented from sliding therefrom by lock washer 324. The detent ring 302 includes an axle sleeve 325 having a key 326 which engages a slot 328 provided in the hub 322 so that rotation of the sleeve 325 will impart rotation to the cap 320. The cap 320 is firmly affixed to the upper end 330 (FIG. 18) of an inner leg assembly 332 and is also cemented to the upper end 334 of each outer leg portion 336 of the legs 124. With this arrangement, oscillation of the cap 320 will cause its associated leg 124 to swing back and forth. Such oscillation is caused by an up and down motion supplied by the cam 252 to the actuator 314 through a connecting pin 340 which is carried by the actuator 314 and which extends through an aperture 342 provided in the housing 122 into engagement with the cam slot 254. Thus, the cam slot 254 causes the pin 340 to move up and down oscillating the actuator 314 which, in turn, oscillates the cap 320 through the medium of the detent ring 302 and the axle sleeve 325. The cap 320 and the inner leg 332 may be made of injection molded, rigid plastic while the outer leg portion 336 is preferably made of a soft pliable plastic such as plastisol.

Each inner leg 332 also includes an end 344 carrying outwardly extending protuberances 346 which pivotally connect an associated foot 230, 232 to the inner leg 332 by engaging an aperture 348 provided on each side of the foot portion 230, 232 at the appropriate location of an ankle. Each foot 230, 232 is connected by a suitable rod 350 to an actuator link 292 in such a manner that a parallelogram action is provided to keep each foot 230, 232 square with the ground 234 (FIG. 23) during fore and aft motion of an associated leg 124.

As previously stated, the detent 288 on the actuator link 292 and the associated spring washer 316 are included in the assembly to facilitate the sitting action of the legs 124. However, during the walking action, the detents 288 are locked in position and the actuator link 292 is, for all practical purposes, a stationary point on the housing 122 while the actuator 314, driven by the cam 249, is a fixed part of its associated leg 124. It should be noted that as the crank shaft 196 rotates in the housing 122, it supplies the aforementioned rocking action between the leg unit 118 and the body unit 112 as well as fore and aft motion of the legs 124. There is no orientation of this fore and aft leg motion with the rocking action since the cam 249 can be in any angular position on the shaft 196.

The cam slot 254 which actuates this fore and aft action of the legs 124 is shown in laid-out form in FIG. 20. Each leg 124 is driven back during approximately 80% of the cam rotation and is driven forward during approximately 20% of the cam rotation. Thus, the cam slot 254 includes two slopes. The slope of the section of the slot 254 which drives a leg 124 forward is four times as great as the slope of the section of the slot 254 that drives the leg back. If a particular leg is on the ground 234, the clutching action between the shaft 196 and the cam assembly 236 is great enough to overcome the small slope of the section of the cam that drives the leg back. Therefore, the leg will be driven back until the driving pin 340 on the actuator reaches the top end of this section of the cam. At that point, the steepness of the slope of the cam slot 254 that drives the leg forward is sufficient to slip the clutch faces 258 and 262 holding the cam assembly 236 stationary until the weight of the toy 110 is shifted to the other foot. At this point, the actuator of the opposite leg will be at a point on the cam where it will, in turn, drive the leg back.

To summarize this action, the difference in slope in the fore and aft sections of the cam in conjunction with the clutching torque will allow a foot 230, 232 to be driven back, but not forward, while the weight of the toy is on that particular foot. In this way, the cam 249 will be slipped rotatably until it coordinates with the rocking

of the leg unit 118 relative to the ground 234 and independent of the rocking of the leg unit 118 relative to the body unit 112.

Although a particular leg is driven back during 80% of the cam rotation, the foot associated with that leg is only on the ground 234 during 50% of the cam rotation. This means that the foot starts its backward motion before that particular foot contacts the ground. The clutch driven cam assembly 236 is also designed to give a constant-velocity stroke to the leg action. The combination of these two factors results in a forward motion of the entire toy 110 at a more or less constant velocity. This avoids fore and aft inertia loads that would tend to make the toy 110 unstable in the forward direction. Fore and aft stability of the toy 110 is also increased by incorporating the parallelogram system coupling the foot to the fore and aft motion of its associated leg. These principles are presented graphically in FIGS. 20-22 wherein the driving pin 340 for the left leg 124 may be considered as starting at point A on the low spot of the cam slot 254. In this position of the driving pin 340, the left leg is at its forward-most position preparatory to starting backward. When the toy 110 is viewed from the back as in FIG. 22, it will be rocking to the left. When the cam slot 254 has rotated until the pin 340 for the left leg is at position B, the left leg will be starting back as indicated and the body unit 112 will be rocking to the right toward an upright position. When the cam slot 254 rotates until the pin 340 for the left leg is at position C, the left leg 124 is still moving back, but has not yet reached the center line of the toy 110. Simultaneously, the body unit 112 is still rocking to the right and has not yet reached an upright position. At point D on the cam slot 254, the left leg 124 is still moving back toward the center line of the toy and the foot 230 is approaching ground contact while the right leg 124 remains in contact with the ground and the body 112 reaches an upright position. At point E, the left foot 230 is in full ground contact and the left leg 124 has reached the center line of the toy 110 while the body unit 112 is beginning to rock to the right and the right leg 124 is elevated. At point F, the left foot 230 is still in full ground contact with the leg moving back past the center line of the toy 110 and the body unit 112 rocking further to the right while the right leg is elevated to a higher position. At point G, the left foot 230 is still in full ground contact with the leg 124 moving further to the rear while the body unit 112 is starting to rock back to the left toward the center line and the right leg 124 is again approaching the ground. At point H, the left foot 230 is still in full ground contact and the left leg 124 is still moving to the rear while the body unit 110 is rocking to the left near an upright position and the right leg 124 is approaching ground contact. At point I, the left leg 124 has reached the end of its backward travel and is ready to start forward, the right foot has reached ground contact while the left foot remains in ground contact and the body unit 112 has rocked to an upright position. At point J, the left foot is elevated and swinging forward while the body unit 112 is rocking to the left and the right foot 230 remains in ground contact. As the pivot pin 340 for the left leg approaches A again, the left foot is still moving forward and has reached its highest elevation and is ready to reverse while the body unit 112 has rocked to its extreme left hand position with the right foot remaining in ground contact.

A modified form of the clutch driven cam assembly is shown in FIG. 32 and is indicated generally at 236a. The clutch driven cam assembly 236a includes a plastic bearing 238a having a hub portion 240a which is mounted in an aperture 242a provided in the bottom wall 162 of the housing assembly 122a in such a manner that the crank shaft 190 is free to rotate in the bearing 238a. The bearing 238a includes an enlarged annular portion 244a having an upper face 246a providing a bearing surface 75 for the lower annular face 262a of a cam assembly 249a.

The cam assembly 249a includes an upper cam half 250a having three unequally spaced pins 360 which depend from the upper cam half 250a and which are engageable with similar spaced apertures (not shown) provided in a lower cam half 252a so that the cam halves 250a and 252a may be connected together with a cam slot 254 being formed in proper orientation which is identical to the cam slot 254 previously described and shown in laid-out form in FIG. 20. The cam 249a may be rotatably mounted on the crank shaft 190 on top of the bearing 238a after which a compression spring 260a and a clutch 362 may be rotatably mounted on the shaft 190 inside the upper cam half 250a in such a manner that an axially extending slot 364 provided on the clutch 362 engages a protuberance 366 provided in the upper cam half 250a in such a manner that the clutch 362 is prevented from rotating while remaining free to reciprocate within the cam half 250a. The clutch 362 includes an upstanding protuberance 368 which is biased, by the spring 260a, into engagement with a notch 370 provided on the under surface of the gear 194.

Since the gear 194 is keyed to the shaft 190 by the key 212 and the clutch 362 is keyed to the cam 249a by the slot 364 engaging the protuberance 366, rotation of the gear 194 by motor 120 would impart rotation to the cam 249a so long as the protuberance 368 is in engagement with the notch 370. However, the protuberance 368 will become disengaged from the notch 370 permitting the gear 194 to rotate without imparting rotation to the cam 249a when the cam 249a meets sufficient resistance. As previously described in connection with the cam assembly 236, the difference in slope in the fore and aft sections of the cam 249a in conjunction with the clutching torque provided by the clutch 362 allow a particular foot to be driven back, but not forward, while the weight of the toy is on that particular foot. In this way, the cam 249a is also slipped rotatably until it coordinates with the rocking of the leg unit 118 relative to the ground 234 and independent of the rocking of the leg unit 118 relative to the body unit 112.

The gear 194 is provided with a transverse slot 372 which permits mounting the gear 194 on the shaft 190 by moving the gear 194 past the key 212. The gear 194 may then be rotated until a notch 374, which is provided on the upper surface of the gear 194, is aligned with the key 212 after which the gear 194 is moved upwardly into locking engagement with the key 212. The key 212 is maintained in locking engagement with the notch 274 by a C-shaped washer 376 which includes an opening 378 and which is moved into position between the gear 194 and the cam 249a by passing the opening 378 over the clutch 362. Thus, the assembly comprising the gear 194, clutch 362, cam 249a and bearing 238a cannot be removed from the shaft 190 until the washer 376 is moved laterally away from the clutch 362. The gear 194 may then be moved downwardly sufficiently to permit rotating it until the slot 372 is aligned with the key 212 permitting the gear 194 to be removed from the shaft 190.

The leg unit 118 shown in FIGS. 17-19 may be modified as indicated at 118a in FIGS. 26-31. The leg unit 118a includes a leg actuating assembly 228 which is identical to that shown and described in connection with FIGS. 17-19, and which will not be described further in connection with FIGS. 26-31.

The major difference between the leg units 118 and 118a resides in the structure of the legs, which are indicated generally at 124a in FIGS. 26-31. Each leg assembly 124a includes an inner housing half 380 and an outer housing half 381 in which an inner leg member 350a is mounted. Each member 350a is connected to an associated actuator link 292 by a right-angle portion 382 which extends through a slotted aperture 383 provided in a leg cap 320a formed integrally with the inner housing half 380. The cap 320a connects a leg 124a to an as-

sociated leg actuating mechanism 228 in the manner previously described for the leg 124. The housing halves 380 and 381 may be secured together by engaging pins 384 provided on each outer housing half 381 in hollow bosses 386 provided on each inner housing half 380. The assembled housing halves 380 and 381 may be pivotally connected to a left foot member 230a and a right foot member 232a by a first set of pins 388 which pivotally connect the ankle portions 389 of the housing halves 380 and 381 to an upper foot portion 390 at the rear portion thereof and by a set of pins 392 which pivotally connect the instep portions 393 of the members 350a to an associated upper foot portion 390 near the front portion thereof. This type of connection produces the parallelogram action previously described in connection with FIGS. 17-19 which maintains the foot 230a and the foot 232a in parallel alignment with the ground 234 (FIG. 28) in all positions of operation of each leg 124a as it is swung by the actuator mechanism 228 during walking operations. The feet 230a and 232a each includes a lower foot portion 394 having offset brackets 396 engageable with pins 398 for connecting the lower foot portion 394 to the upper foot portion 390. The foot portions 390 and 394 include inner edges 400 which are free to reciprocate with respect to each other as indicated by arrows 402 in FIG. 29. The edges 400 are biased apart by a spring member 404 which is cradled in notches 406 provided in an associated lower foot portion 394 and which is engaged by a depending tab 408 provided on the upper foot portion 390. The amount that the edges 400 may separate from each other is limited by a stop member 410 (FIG. 29) which depends from the upper foot portion 390 and which is engageable with the lower foot portion 394. This construction constitutes resilient means in the leg unit 118a which facilitates the raising of a particular foot 230a, 232a and results in more side-to-side motion of the leg unit 118a for a given angular relation between the body unit 112 and the leg unit 118a in a given rocking mode. In addition, as clearly seen in FIG. 29, the lower foot portion 394 slopes downwardly and laterally from its inner edge 400 to an apex portion 394a which is positioned intermediate the inner edge 400 and an outer edge 400a while lying closer to the inner edge 400.

It has been found that without such resilient means, the toy 110 is not self-starting in a forward direction at lower rocking frequencies. The doll 110 is provided with a 32.8:1 gear reduction and draws about 250 millamps. With this gear reduction, it has a crank frequency of 116 r.p.m. at 3 volt terminal voltage. The toy will operate down to 67 r.p.m. at 1.9 volts terminal and the batteries 116 (2 D-cells in series) will have a life of about 3.6 hours continuous duty. However, the toy is not self-starting without the resilient means in the leg unit 118a. It has been found, on the other hand, that a gear reduction of 25:1 provides a sufficiently high crank frequency for making the toy self-starting. With this gear ratio, the toy will rock at 150 r.p.m. at 2.8 volts and 72 r.p.m. at 1.9 volts terminal. The current draw then increases to 370 millamps and the useful life of the batteries decreases to about 1.5 hours. Thus, the resilient means in the leg unit 118a is an important feature of the invention because it permits increasing battery life and reducing power consumption by employing a higher gear ratio for driving the leg unit 118a. The rocking action creates a side-to-side motion which, in conjunction with the mass of the toy, is sufficient to lift the feet off the ground. This appears to meet the objective of defining a region of operating range of the toy 110 for minimum power requirement and maximum rocking stability. A configuration that is self-starting is associated with a large momentum of the body unit 112. This means either a heavy body unit, large amplitude of driving function or high speed of rocking. This, on the other hand, is not compatible with the requirement of low power input or broad region of operating range. It is to be noted that this

feature could either be sacrificed or a mechanism could be built into the toy to boost the amplitude or speed temporarily during the starting sequence and returning it to normal design condition after a motion is established. Since it is not desirable to sacrifice this feature and since it would be expensive to build such mechanism into the doll to boost the amplitude or speed temporarily, it is preferred to employ the resilient means in the leg unit 113a.

A shoe sole 412 having a high co-efficient of friction is affixed to the bottom of the lower foot portion 394 to increase traction between the ground 234 and an associated foot 230a, 232a. The feet 230a and 232a are each covered with a housing member 414 which is suitably decorated to simulate a shoe. The lower portions of the legs 124a are also covered with a housing member 416 in the form of a sock which may be folded down over the housing member 414 as shown in FIGS. 28 and 29.

Referring now to FIG. 26, power is supplied to the motor 120 through a first electrical lead 418 and a second electrical lead 420 which may be connected to a switch mechanism, indicated generally at 422, and an electrical leaf spring 424 respectively. The leaf spring 424 and the switch 422 each include battery-engaging portions 426 for completing a circuit from the batteries 116 (FIG. 17) to the motor 120 through the switch 422 and the leads 418 and 420.

The switch 422 includes a toggle 428 having a finger-engaging portion 430 which extends through the back of the body unit 112 as shown in FIG. 28 and a weight-engaging portion 432 which is engageable with a weight 434. The weight 434 includes pins 436 for swingably mounting the weight 434 in the body shell 114 on brackets 438 provided in the upper portion thereof. The switch 422 also includes a leaf spring 440 which may be mounted in the body shell 114 in such a manner that it completes a circuit through the battery engaging portion 426 of switch 422 when the switch is actuated. Should the body unit 112 fall over when the motor 120 is energized, the weight 434 will trip the switch 422 de-energizing the motor 120.

While the particular walking toys herein shown and described in detail are fully capable of attaining the objects and providing the advantages hereinbefore stated, it is to be understood that they are merely illustrative of the presently preferred embodiments of the invention and that no limitations are intended to the details of construction or design herein shown and described in detail other than as defined in the appended claims.

What is claimed is:

1. A walking figure comprising: a substantially upright torso having a pair of depending substantially rigid legs separately pivoted thereto and relative to each other and having ground-engaging feet at their lower ends; said legs each being mounted on said torso for fore and aft swinging movement relative thereto substantially about a transverse axis and for limited lateral swinging movement relative to said torso about a fore and aft axis; drive means in said figure and arranged to swing said legs in opposite fore and aft directions relative to said torso; said drive means being arranged to swing at least one leg laterally relative to said torso to thereby throw the weight of said figure onto said one leg and to swing the other leg forwardly while also swinging said one leg rearwardly to move said torso forwardly, said ground-engaging feet each having an inner edge, an outer edge and a portion sloping downwardly and laterally from said inner edge to an apex portion, said apex portion being located intermediate said edges at a position which is closer to said inner edge than to said outer edge whereby said apex acts as a fulcrum when the weight of said figure is shifted.

2. A walking figure as defined in claim 1 wherein said drive means is arranged to swing the foot end of said one leg laterally inwardly relative to said torso to thereby

6 throw the weight of said figure thereon while swinging said other leg forwardly and wherein said ground-engaging feet are connected to associated legs by connecting means which maintain said feet substantially parallel to said ground during fore and aft swinging of said legs.

3. A walking figure comprising: a substantially upright torso; a leg assembly comprising a frame portion pivoted to said torso on a generally fore and aft axis; a pair of legs depending from and separately pivotally mounted, with respect to each other, on said frame portion for fore and aft swinging movement thereon; and drive means drivingly connecting said frame and torso to cyclically oscillate them relative to each other about said fore and aft axis, said drive means including cam means for drivingly connecting said legs to said drive means, said cam means including a cam slot having a predetermined configuration; and actuator means connected to said legs, said actuator means including connecting pin means engaged in said cam slot to cyclically swing said legs in fore and aft directions on a predetermined cycle determined by said predetermined configuration of said slot; said drive means being arranged to relatively oscillate said torso and frame about said fore and aft axis while said cam means and said actuator means swings said legs in such timed relation that the weight of said figure is thrown onto one of said legs by an oscillation of said torso and frame while the other leg is being swung forwardly.

4. A walking figure as defined in claim 3 wherein said actuator means is drivingly connected to each of said legs through resiliently releasable detent means whereby said legs may be manually swung to a generally sitting position.

5. A walking figure as defined in claim 3 wherein said drive means includes an electric motor and a motor control switch means for deenergizing said motor in response to tilting said figure an amount substantially greater than any tilt thereof caused by walking movements of said figure.

6. A walking figure comprising: a substantially upright torso having depending legs, each of said legs including an upper end and a lower end, said upper ends of said legs being pivotally connected to said torso at predetermined pivot points for fore-and-aft swinging movement, said lower ends being engageable with a surface upon which said figure is adapted to walk; drive means in said figure and arranged to swing said legs in opposite fore-and-aft directions relative to said torso and for reciprocating said pivot points in a vertical plane; and resilient means associated with each of said legs, said resilient means having a predetermined bias which is overcome when the lower end of an associated leg engages said surface, whereby energy is stored in said resilient means for assisting said drive mean in lifting said lower ends from said surface during reciprocation of said pivot points in said vertical plane.

7. A walking figure comprising: a substantially upright torso; a leg assembly comprising a frame portion pivoted to said torso on a generally fore and aft axis; a pair of legs depending from and separately pivotally mounted, relative to each other, on said frame portion for fore and aft swinging movement thereon; drive means drivingly connecting said frame and torso to cyclically oscillate them relative to each other about said fore and aft axis; and slip clutch means connecting said drive means to said legs to cyclically swing said legs in fore and aft directions, said slip clutch means controlling said drive means in such a manner that said legs cannot be swung by said drive means unless the weight of said figure is supported by only one leg, said drive means being arranged to relatively oscillate said torso and frame and to swing said legs in such timed relation that the weight of said figure is thrown into one of said legs by an oscillation of said torso and said frame while the other leg is being swung forwardly.

21

8. A walking figure comprising:
 a substantially upright torso;
 a leg assembly comprising a frame portion pivoted to
 said torso on a generally fore and aft axis;
 a pair of legs depending from and separately pivotally
 mounted with respect to each other on said frame
 portion for fore and aft swinging movement thereon;
 drive means drivingly connecting said frame and torso
 to cyclically oscillate them relative to each other
 about said fore and aft axis; and
 10 cam means connecting said drive means to said legs to
 cyclically swing said legs in fore and aft directions,
 said cam means having a predetermined configuration
 for swinging each leg in one direction relative
 to said torso more slowly than it is swung in the other
 16 direction, said drive means being arranged to relatively
 oscillate said torso and frame and to swing
 said legs in such timed relation that the weight of said
 figure is thrown onto one of said legs by an oscillation
 of said torso and frame while the other leg is
 20 being swung forwardly.

9. A walking figure as defined in claim 8 including
 slip clutch means connecting said drive means to said
 cam means, said slip clutch means controlling said drive
 26 means in such a manner that said legs cannot be swung
 by said drive means unless the weight of said figure is
 supported by only one leg.

10. A walking figure comprising:
 a substantially upright torso;
 a leg assembly comprising a frame portion pivoted to
 said torso on a generally fore and aft axis;
 a pair of legs depending from and separately pivotally
 mounted, relative to each other, on said frame por-
 20

22

tion for fore and aft swinging movement thereon;
 and
 drive means drivingly connecting said frame and torso
 to cyclically oscillate them relative to each other
 about said fore and aft axis, said drive means also
 being drivingly connected to said legs to cyclically
 swing said legs in fore and aft directions, said drive
 means being arranged to relatively oscillate said
 torso and frame and to swing said legs in such timed
 relation that the weight of said figure is thrown onto
 one of said legs by an oscillation of said torso and
 frame while the other leg is being swung forwardly,
 said drive means being further arranged to start each
 leg to swing rearwardly before the weight of said
 figure is shifted thereto.

11. A walking figure as defined in claim 3 wherein said
 drive means also includes an electric motor and crank
 means connecting said motor, frame and torso together
 to form said driving connection.
